UNITED STATES PATENT OFFICE.

FREDERICK W. HINSEY, OF EUDORA, KANSAS, ASSIGNOR OF ONE-HALF TO
EDWARD ELVIN WILSON, OF SAME PLACE.

TINNER'S STAKE.

SPECIFICATION forming part of Letters Patent No. 506,284, dated October 10, 1893.

Application filed June 28, 1893. Serial No. 479,063. (No model.)

To all whom it may concern:

Be it known that I, FREDERICK W. HINSEY, a citizen of the United States, residing at Eudora, in the county of Douglas and State of 5 Kansas, have invented a new and useful Tin-
ner's Stake, of which the following is a speci-
fication.

My invention relates to a tinner's stake, and it has for its object to provide a simple, in-
10 expensive, and efficient device combining the various sizes of stakes ordinarily employed by tinnings and usually consisting of a series of independent cylindrical parts or sections. It will be understood that it is the common
15 practice to employ these stakes, which are of different diameters, independently, and it is my object to combine them to form a single implement having independently adjustable members or sections, which are of different
20 diameters and either of which may be used independently of the others, to economize space and retain all of the parts in convenient positions for use.

Further objects and advantages of my in-
25 vention will appear in the following descrip-
tion, and the novel features thereof will be particularly pointed out in the appended claims.

In the drawings: Figure 1 is a view of a stake
30 embodying my invention applied to a bench, the members or sections being folded. Fig. 2 is a central longitudinal section of the same. Fig. 3 is a view showing one of the sections extended for use. Fig. 4 is an end elevation.
35 Similar numerals of reference indicate cor-
responding parts in all the figures of the drawings.

The stake comprises a series of telescoping
40 members or sections, which are tubular and are of graded diameters, in order that they may fit snugly yet slidably one within the other. The device which is illustrated in the drawings is provided with five of these telescoping sections or members, which are num-
45 bered successively 1, 2, 3, 4, and 5, beginning with the member or section of largest diameter. The terminal or smallest member or section may be solid, as shown. The members or sections are preferably formed of steel or
50 similar strong material, and the member or section 1 is provided near its rear end with a

transversely-disposed stop-pin 6, to limit the movements of the members or sections when repressed. The members or sections are, fur-
thermore, of different lengths whereby, when 55 folded as shown in Fig. 1, each member pro-
jects slightly beyond the outer end of the next larger member, or the member into which it is fitted, to enable the operator to grasp either member to extend the same for use. The sec-
60 tion 1 is secured in operative position to a bench 7, a part of which is shown in Figs. 1 and 2, by means of clips or keepers 8, through which, however, said member or section is
65 slidable in order to enable it to be extended when it is desired to use the same.

From the above description it will be ap-
parent that the stakes of all sizes required in
ordinary practice are thus arranged in the
compass of a single stake and are held in con-
70 venient position for immediate use. In se-
lecting the size of member which is desired
for a particular purpose, the same may be ac-
complished readily and quickly owing to the
relative and comparative arrangement of 75
parts; and when the selection is made the de-
sired member or section may be extended to
the operative position without affecting the
others or requiring any special adjustment
or handling of those members which are not 80
required.

Various changes in the form, proportion,
and the minor details of construction may be
resorted to without departing from the prin-
ciple or sacrificing any of the advantages of 85
this invention.

Having described my invention, what I
claim is—

1. A tinner's stake, comprising a series of
telescoping independently extensible mem-
90 bers or sections, each member or section form-
ing a guide and holder for the member or sec-
tion of next smaller diameter substantially
as specified.

2. A tinner's stake, comprising a series of
telescoping members or sections which in-
95 crease successively in length from the mem-
ber of largest diameter to that of smallest di-
ameter, substantially as specified.

3. A tinner's stake, comprising a series of
100 telescoping sections of graded lengths, the
member or section of greatest diameter being

provided with a stop to limit the rearward movement of the members or sections, substantially as specified.

4. A tinner's stake, comprising a series of 5 telescoping members or sections, in combination with fixed guides or keepers in which the member or section of largest diameter is slidably fitted, substantially as specified.

In testimony that I claim the foregoing as my own I have hereto affixed my signature in the presence of two witnesses.

FREDERICK W. HINSEY.
